[57] CLAIM

The ornamental design for a reinforcing and protector element for the edges of pallet goods, as shown and described.

DESCRIPTION

FIG. 1 is a perspective view of a reinforcing and protector element for the edges of pallet goods showing my new design;

FIG. 2 is a perspective view as seen from the other side thereof;

FIG. 3 is a perspective view of FIG. 1 with both of the reinforcing members removed for clarity of illustration; and

FIG. 4 is a perspective view of one of the reinforcing members of FIG. 1 shown separately for clarification of illustration.
